UNITED STATES PATENT OFFICE

WILLIAM H. MUSSEY, OF CHICAGO, ILLINOIS, ASSIGNOR TO PULLMAN CAR & MANUFACTURING CORPORATION, OF CHICAGO, ILLINOIS, A CORPORATION OF ILLINOIS

CAR VENTILATOR

Application filed March 1, 1929. Serial No. 343,694.

The invention relates to ventilators of the eduction type and is especially adapted for use with exhaust control mechanism designed for operation from the inside of the car.

5 The ventilator is operable in either direction of car movement and functions to exhaust the air from the car thru a central opening defined by contiguous ports of a pair of laterally extending exhaust funnels converging at the opening, the ventilator being further equipped with a plurality of air ducts flanking the funnels and converging with their contiguous port walls at the longitudinal center line of the car and ventilator.

10 15 The purpose of a ventilator having its operating parts disposed as above outlined is to accommodate within a relatively small compass, ducts and funnels of the size and number required to adequately perform their several functions within the structural and operating limitations imposed.

It is therefore an object of the invention to provide a ventilator having ducts and funnels of maximum capacity assembled in operative relation and within a comparatively small compass.

20 25 A further object is to provide adjustable means manually controlled for regulating the rate of air exhaust independently of the direction of car movement.

The foregoing and other objects are attained by the mechanism illustrated in the accompanying drawings, in which—

30 35 Fig. 1 is a plan view of a portion of a car roof fitted with a ventilator built in accordance with the invention, a corner of the ventilator being broken away to show the relative positions of duct and funnel walls;

40 45 Fig. 2 is a vertical sectional view taken on line 2—2 of Fig. 1 thru the exhaust funnels of the ventilator and showing the draft control valve mechanism in operative relation thereto;

Fig. 3 is a bottom plan view of the control valves operating mechanism, showing the valves closed;

50 55 Fig. 4 is a vertical sectional view longitudinally thru one of the control valves and individual operating gear taken on line 4—4 of Fig. 3;

Figs. 5 and 6 are similar views transversely thru the valves taken on line 5—5 of Fig. 4 and showing the valves in closed and fully opened positions, respectively;

Fig. 7 is the toggle link connecting the 55 crosshead on the worm shaft to the pivot bracket on adjacent valve;

Fig. 8 is the toggle link crosshead;

Fig. 9 is the worm shaft end bushing, shown with its underside up, and 60

Fig. 10 is the toggle link pivot bracket on the valves.

In the drawings, 10 represents the roof of the car upon which is mounted the ventilator shaped to conform to the curvature of the 65 roof and comprising a base plate portion 11 having an opening 12 intermediate its sides and ends and registering with an opening 13 in the roof framed by roof carlines 14 and longitudinal connecting and supporting 70 members 15 and secured by rivets 16 and 17 respectively. Upon the base plate is mounted the ventilator superstructure embodying the oppositely disposed exhaust funnels 18 and the air ducts 19 flanking the funnels and 75 converging at the longitudinal center of the ventilator in planes intersecting those occupied by the funnels. The ducts and funnels are completed by the addition of a cover plate 20 forming the ventilator top, the cover plate 80 being supported upon the duct and funnel air deflecting walls presently to be described.

The supporting deflector walls comprise the duct air gathering plates 21 and breast plates 22 and with the transversely extending connection plates 23 combine with the base and cover plates 11 and 20 to form a rigid structure adapted to be applied to the car as a unit and assembled with the control mechanism hereinafter referred to. The 90 funnel space between the air deflecting breast plates 22 on opposite sides of the longitudinal center of the ventilator and lateral connection plates 23 is fitted with a pair of downwardly converging partition plates 24 to 95 divide the opening 13 into separate funnel ports 26 adapted to be controlled by separate valves 27 independently operable to regulate the air exhaust thru one or the other of the funnels 18. To further define the valve con- 100

- trolled ports of funnels 18, connection plates 23 are extended downwardly below the roof framing, and with associated plates 25 supported upon roof frame longitudinals 15, provide extended funnel openings projecting well below the supporting framework and ventilator base. There is thus provided a pair of downwardly converging funnels 18 having contiguous exhaust ports 26 in a plane below the base 11 of the ventilator and a plurality of air ducts 19 arranged in pairs on opposite sides of the funnels and converging at the longitudinal center line of the ventilator in a plane above the base plate 11 and the car roof 10.
- It will be apparent that the space above the roof opening 13 occupied by a central air chamber with end walls in ventilators heretofore employed, is herein utilized to accommodate the air ducts 19 having receiving ports 30 of ample proportions and relatively small eduction ports 29 designed to enhance the ejector value of the air currents issuing from said ports for accelerating the exhaust of the air from the funnels 18. The saving in space afforded by the elimination of the customary central air chamber may be devoted to the increase in area of the receiving ports 30, a reduction in the width of the ventilator, or both of these objects effected, depending upon the limitations or restrictions of equipment and for operation as before noted. To prevent the entrance of cinders or other foreign matter driven by the wind against the funnel openings 28, wire screens or other material may be used to cover the openings or rotatable air baffles installed therein to break the force of the wind blowing into the funnels.
- Secured to the roof framework longitudinals 15 and to ceiling plate 31 in any suitable manner, and entirely surrounding the roof opening 18 and depending portions of funnel plates 28, 24 and 25, is the valve assembly comprising a rectangular frame 32, having end walls 33, and partition 34, all preferably cast as a unit to insure precision in operation of the movable parts of the valve gear fitted thereto. The partition 34 is centrally located with respect to the funnel ports 26 of the ventilator in alignment with partition plates 24 and provides an abutment 35 along the lower margin of the partition for the free edges of the valves 27 on opposite sides thereof. The valves are pivotally mounted on hinges 36 secured to valve frame 32 as best shown in Figs. 2, 3, 5, and 6, and manipulated by gear having positive connection with the valves as indicated in these figures.
- As shown in Figs. 3 and 4, the valve frame 32 is formed with laterally projecting gear supporting extensions 37 having openings 38 conforming to the shape of the bushing 39 shown in Fig. 9 and adapted to receive the bushings with their base portions flush there-

with. These bushings are removably supported upon shaft housings 41 having openings to receive the bearing collars 42 on the bushings which are held by screws 40 taking openings 43 in the bushings and 44 in the housings 41. The housings 41 are secured to valve frame 32 and lateral extensions 37 by screws 9 or the like and provided at their lower extremities with laterally projecting brackets 45 providing seats for the driving worms 47 upon which the crossheads 48 shown in Fig. 8, are mounted for movement. The operating worms 47 are rotatably held at their upper ends in bearing collars 42 on bushings 39 and at housing brackets 45 by the upwardly projecting end portions 49 of operating rods 50 journaled in the brackets 45 and held in operative position by washers 51 fixed to rods 50 immediately below the brackets as best shown in Figs. 3 to 6, inc. The upwardly projecting ends 49 of the rods have telescopic engagement with the worms 47, in the lower ends of which are openings 52, and there secured by pins 53 taking the respective rods and worms.

The crossheads 48 are formed with a trunnion portion 54 to provide a pivotal bearing for the respective toggle links 55 having suitable openings 56 to receive said trunnions. The crossheads are further provided with openings 57 threaded to receive the operating worms 47 and located at approximately the center of gravity of the piece, and other holes 58 designed in the present embodiment to receive a pair of guide rods 59 arranged on opposite sides of the respective worms and in a plane removed from the center of gravity of the crosshead to avoid tilting of the crosshead and resultant pinching of worm and guide rods under operating stresses imposed on the trunnions 54. The guide rods 59 serve to prevent rotation of the crosshead about the operating worm axis and functions to maintain the trunnions 54 in precise operating relation to the toggle links 55. As shown in the drawings, the guide rods extend from the housing brackets 45 upwardly to the upper securing flanges 60 at the top of the housings and secured at their respective ends by riveting over or otherwise. The toggle links 55 are also pivotally journaled on trunnion brackets 61 secured to or formed with the respective valves 27. The links are held in operative engagement with their respective trunnions by pins 62 or otherwise and suitable valve operating wheel handles 63 are secured to operating rod 50 for convenient manipulation of the device.

It will be observed that the exhaust funnels 18 and valves 27 are severally indicated for operation respectively independent of the other funnel and valve. To guard against possible failure of one or the other of the valve gear mechanisms to properly function in the regulation of the rate of flow of air

thru one or both of the exhaust funnels, the regulation of both exhaust funnels with only one of the valves 27 may be effected by establishing communication between the funnels 18. This may be achieved by the simple expedient of providing port holes 65 in partition 34 of the valve frame assembly as indicated in Fig. 4, or in the convergent funnel partition plates 24, as desired.

In operation, assuming the car to be moving in the direction indicated by the arrow at the upper center of Fig. 1, the oncoming air will enter the ducts 19 through the large ports 30 and impinge upon the breast plates 22 and be directed thereby and the gathering plates 21 to the relatively small eduction ports 29 at the sides of the ventilator and be there expelled and swept across the respectively adjacent exhaust funnel openings 28.

As the air sweeps past the funnel openings it carries with it the air exhausted from the car interior when the valves 27, controlling the respective funnels, are opened, the intensity of the flow depending upon the extent of the respective valve openings. In the event that openings 65 in the partition 34 are utilized the magnitude and intensity of the flow will be governed by the opening of one valve alone or both at the same time, and the extent of such openings. Sweeping past the funnel openings 28, the air streams enter the openings 29 of the ducts 19 at the ventilator end opposite to the facing in the direction of ventilator movement. By virtue of the vacual condition of the space immediately adjacent the converging breast walls 22 resulting from their movement thru the enveloping atmosphere, the air stream will be directed along the breast walls without eddying and thru contiguous ports 30. Eddying of the air currents is avoided by the retrograde surfaces presented by the converging breast plates 22 receding to a point between contiguous ports 30 thru which the vitiated air currents find their respective exits. Thus arranged, the walls 22 follow the normal trend of the air flow to thereby maintain only an operating minimum of the vacual condition necessary to effect a smooth and steady flow of the air streams thru their respective ports 29.

The valve gear mechanism is operable upon manipulation of handles 63 for turning the operating rods 50 and worms 47. Assuming one or both of the valves 27 to be in the closed condition indicated in Figs. 2 to 5, inc., and their respective crossheads 48 in the raised position, best shown in Fig. 4, the valves being held closed by the links 55, the valve or valves may be dropped to the extreme open position indicated in Fig. 6, or any intermediate position as required. In the event that partition plates 24 or 34 are perforated as hereinbefore described, it will be necessary to open but one valve to obtain the benefit of

both exhaust funnels 18, as will be obvious, otherwise but one funnel becomes operative upon opening of the respective valves.

It will be noted that there have been produced a ventilator and associated controlling mechanism adapted for application to the car roof in separate units, and that the several units combine to produce an economical installation of maximum capacity and of relatively small compass. It is also conceivable that within the scope of the invention the valve operating gear frame may be secured to and supported from the ventilator walls surrounding ports 26 and adapted for removal or application with the ventilator should conditions warrant such arrangement of the units.

What I claim is:

1. A ventilator comprising a base plate having an opening therein, a plurality of air ducts and exhaust funnels having walls converging in planes intersecting said opening, plates uniting said walls extending thru said opening and defining contiguous portions of said funnels, and a top plate in substantial parallelism with said base plate and connecting said walls.

2. A ventilator comprising a base plate having an opening therein, a plurality of air ducts and exhaust funnels having walls converging in planes intersecting said opening, a top plate supported on said walls, and other plates uniting said walls and plates extending thru said opening and defining contiguous portions of said funnels.

3. In a car ventilator comprising a base plate cambered transversely of the car and having an opening therein, a plurality of air ducts spaced apart longitudinally of the plate and diverging laterally from the center thereof, and oppositely disposed exhaust funnels extending transversely of the car between said air ducts and converging within said opening.

4. In a car ventilator, the combination including roof framing longitudinal and transverse members defining an opening in the car roof, laterally extending exhaust funnels converging within said opening, and funnel extension and connection plates projecting downwardly below said frame work to provide exhaust port openings, certain of said funnel plates constituting in said assembly a partition bisecting said openings.

5. A ventilator for cars comprising a base plate having an opening communicating with the car interior, a pair of laterally extending exhaust funnels converging within said opening, drop valves for closing said opening, and independently operable mechanism for raising and lowering said valves.

6. In a car ventilator, the combination including roof framing longitudinal and transverse members defining an opening in the car roof, a pair of oppositely extending ex-

4
E
base, funnels converging within said opening, valves for closing said opening, independently operable toggle link mechanism controlling said valves, and a unitary structure supporting said mechanism and valves surrounding said opening for securing the assembly to said framing.

5
10
15
20
25
17. In a car ventilator, the combination including roof framing longitudinal and transverse members defining an opening in the car roof, a pair of oppositely extending exhaust funnels converging within said opening, valves for closing said opening, independently operable toggle link mechanism controlling said valves, and a unitary structure supporting said mechanism and valves surrounding said opening for securing the assembly to said framing, said structure including a partition bisecting said opening and providing an abutment for said valves.

In witness whereof I have hereto set my hand this 21st day of February, 1929.

WILLIAM H. MUSSEY.
